(57) **CLAIM**

The ornamental design for a clothes hanger possessing extension rods, as shown and described.

DESCRIPTION

This application is related to U.S. Design patent application Ser. No. 29/615,940, filed on Aug. 31, 2017, entitled “Clothes Hanger,” U.S. Design patent application Ser. No. 29/615,944, filed on Aug. 31, 2017, entitled “Clothes Hanger,” U.S. Design patent application Ser. No. 29/615,952, filed on Aug. 31, 2017, entitled “Clothes Hanger,” and U.S. patent application Ser. No. 15/693,015, filed on Aug. 31, 2017, entitled “Clothes Hanger Possessing Extension Rods.”

FIG. 1 is a perspective view of a clothes hanger possessing extension rods showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines shown form no part of the claimed design.
